REFRIGERATOR TRAY LOOSENING MEANS

Lee S. Chadwick, Shaker Heights, Ohio, assignor
to Perfection Stove Company, Cleveland, Ohio,
a corporation of Ohio

Application March 12, 1935, Serial No. 10,678

1 Claim. (Cl. 62—108.5)

In the use of domestic refrigerating apparatus it is usually quite difficult to remove the trays in which ice cubes are frozen, desserts chilled, or other substances kept at sub-freezing temperatures, from the freezing chambers because the parts become frozen together, so to speak.

It is the purpose of this invention to provide simple and inexpensive yet very effective and easily operated means for loosening or dislodging the trays.

According to the present preferred embodiment of the invention this means consists of a detached member disposed beneath the tray and having a greater transverse than vertical dimension and being provided with an operating handle by means of which it may be tilted or rocked so as to lift the tray and thus loosen it.

In order to maintain the maximum area of contact between the bottom walls of the tray and chamber for heat transfer purposes, the bottom wall of the chamber is provided with a depression for the accommodation of the member which depression is of a depth at least as great as the vertical dimension of the member.

An embodiment of the invention is illustrated in the accompanying drawing and while I shall proceed to describe the same in detail, it will be understood that the invention is not limited to the structural features set out in the specification further than is required by the terms of the claim annexed hereto.

In the drawing, Fig. 1 is a perspective view showing a part of a refrigerating apparatus, including the freezing chamber and trays, equipped with the invention; Fig. 2 is a similar view of the member by which a tray is lifted; Fig. 3 is a fragmentary longitudinal section through the freezing chamber and tray in the vertical plane of the lifting member, and Fig. 4 is a front elevation, partly in section, the plane of section being indicated by the line 4—4 of Fig. 3.

A typical cooling unit or evaporator of a refrigerating apparatus is shown in the drawing, the same being designated 1, and it contains a freezing chamber 2. One or more trays are adapted to be placed within the chamber 2, the purpose for which the trays are to be used determining their size and proportions, and these factors, in turn, determine the number of trays that can be accommodated. In the present illustration, two trays 3 are shown of the kind used for making ice cubes, and accordingly they are fitted with the usual partitions 4.

The bottom wall of the freezing chamber 2 is provided with elongated, semi-cylindrical depres-

sions 5 that open, at their forward ends through the open front of the chamber and accommodate the body portions 6 of members 7 by which the trays 3 are adapted to be lifted. The body portions 6 are generally semi-cylindrical, having well rounded edges, and correspond in depth with the recesses 5, so that when occupying said recesses their top surfaces are practically flush with the bottom wall of the freezing chamber. Operating handles 8 depend from the forward ends of the body portions 6 and the same serve as weights for normally retaining the body portions 6 in position with their top surfaces horizontal.

When the apparatus is in use, practically throughout the intervals between defrosting periods the trays 3 are frozen tight to the bottom wall of the freezing chamber, all parts being covered more or less with a coating of frost, and when it is desired to remove a tray, the handle 8 of the corresponding member 7 is swung to one side or the other, thereby to rock the body portion 6 and lift the tray, thus breaking it loose from the wall of the chamber 2. The member 7 is then withdrawn from the depression 5 and laid aside, after which, by means of its handle 9, the tray may be slid out of the freezing chamber. Before replacing the tray, the member 7 is returned to its former position and inasmuch as its top surface is substantially flush with the bottom wall of the chamber, it offers no interference with the insertion of the tray.

While the tray loosening means or device is herein illustrated as semi-circular in cross section, it will be understood that the cross section of the device may have any one of many different shapes so long as that selected will have the effect of increasing its vertical dimension when the device is rocked.

Having thus described my invention, what I claim is:

In combination, an open front freezing chamber of a refrigerating apparatus and a tray resting upon the bottom wall of said chamber, said bottom wall having an elongated substantially semi-cylindrical depression that opens outwardly through the open front of the chamber, and a member having a substantially semi-cylindrical body portion occupying said depression and a weighted handle depending from its end beyond the open front of the chamber, said weighted handle serving to normally retain the member in position with the top face of its body portion in a substantially horizontal plane.
